(57) **CLAIM**

The ornamental design for a barrel shaped table, as shown and described.

DESCRIPTION

FIG. 1 is a perspective view of a barrel shaped table;
FIG. 2 is a front elevational view thereof;
FIG. 3 is a rear elevational view thereof;
FIG. 4 is a right-side elevational view thereof, the left-side elevational view being a mirror image;
FIG. 5 is a top plan view thereof; and,
FIG. 6 is a bottom plan view thereof.
The broken line showing of the barrel shaped table forms no part of the claimed design.
